IMIDAZOL THIOPHAN DERIVATIVES AND
PROCESS FOR THE MANUFACTURE OF
SAMEOtto Schnider, Jean-Pierre Bourquin, and André
Grüssner, Basel, Switzerland, assignors to
Hoffmann-La Roche Inc., Nutley, N. J., a cor-
poration of New JerseyNo Drawing. Application March 29, 1945, Serial
No. 585,570. In Switzerland April 26, 1944

19 Claims. (Cl. 260—309)

1

Biotin, which is of vital importance for many an organism, was recognised to be a derivative of 3,4-(2'-oxo-tetrahydroimidazol)-thiophan.

It has now been found that thiophan-one-(3)-carboxylic acid esters can be used as starting materials for the manufacture of derivatives carrying in position 2 an alkyl radical or an omega-substituted alkyl radical. Compounds carrying, apart from alkyl radicals, for instance the following radicals, may be employed:—omega-10 hydroxyalkyl-, omega-alkoxyalkyl-, omega-aryl-alkyl- or omega-halogenalkyl-radicals.

The thiophan-one-(3)-carboxylic acid esters (I), which carry a suitable substituent in position 2, are initially converted into the corresponding cyanohydrins (II) by means of hydrocyanic acid. The same are saponified without further purification and the resulting dicarboxylic acids (III) esterified. The 3-hydroxythiophan-3,4-dicarboxylic acid esters (IV), substituted in position 2, are oils capable of being distilled. Upon reacting with halides of phosphorus and sulphur, e. g., thionyl chloride, they are transformed into the 3-chlorine esters (V). By means of reducing agents the halogen can be eliminated, whereby the thiophan-3,4-dicarboxylic acid esters (VI), substituted in position 2, are obtained. From these the way leads to the corresponding acid azides, either by preparing the hydrazides (VII) by means of hydrazin hydrate and treating them with sodium nitrite, or by converting the free acids (VIII) obtained by saponification into the acid chlorides (IX) and treating the latter with sodium azide. By heating with alcohols, the 3,4-di-(carbethoxy-amino)-thiophans (XI), substituted in position 2, are obtained from the azides. On warming with hydrogen halides, e. g., hydrobromic acid, they are converted into the salts of the corresponding 3,4-diamino-thiophans (XII) substituted in position 2. By stirring with 40 phosgene in a weakly alkaline solution, the d,1-3,4-(2'-oxo - tetrahydroimidazol)-2-X-thiophans (XIII) are obtained therefrom.

In these formulae R stands for lower alkyl, and X is an alkyl radical or an omega-substituted alkyl radical.

This synthesis of compounds with the bicyclic system XIII is characterised in that the amino groups needed for the second ring closure are built up at the thiophan ring in cis-position. Only in this position the setting up of a second ring with 5 ring atoms is possible. That the cis-position is in fact present can be proved in the course of the syntheses by the fact that the dicarboxylic acids (VIII) change into acid anhydrides with great ease on warming with acetic anhydride.

The new compounds are intermediate products for the manufacture of pharmaceutically employable substances showing the activity of biotin.

Example 1

80 parts by weight of finely powdered potassium cyanide are added to a solution of 188 parts by weight of 2-methyl-3-oxo-thiophan-4-carboxylic-acid-ethyl-ester in 500 parts by volume of ether. While stirring and cooling well, 90 parts by volume of concentrated hydrochloric acid are added dropwise in the course of about 2 hours. After evaporation of the ether, 300 parts by volume of ethyl alcohol and 300 parts by volume of concentrated hydrochloric acid are added to the remaining 2-methyl-3-hydroxy-3-cyano-thiophan-4-carboxylic-acid-ethyl-ester; saponification is effected by first slowly distilling off the alcohol and then allowing the product to stand in a boiling water bath for another 2 hours. By concentration in vacuo, 2-methyl-3-hydroxy-thiophan-3,4-dicarboxylic acid is obtained, which can be converted into the 2-methyl-3-hydroxy-thiophan-3,4-dicarboxylic-acid-diethyl-ester without further purification by means of ethyl alcohol and hydrochloric acid. It boils at a pressure of 0.05 mm. at 101 to 102° C. as an almost colourless, viscous oil.

262 parts by weight of 2-methyl-3-hydroxy-thiophan-3,4-dicarboxylic-acid-diethyl-ester are dissolved in 500 parts by volume of chloroform and successively treated with 80 parts by volume of pyridine and 119 parts by volume of thionyl chloride while cooling well with ice. The product is first allowed to stand for 2 hours and then heated for about 40 minutes in a boiling water bath until the evolution of gas has ceased. Thereupon, the product is poured on ice, divided in a separating funnel and washed with water and dilute sodium carbonate solution until neutral reaction sets in. The 2-methyl-3-chloro-thiophan-3,4-dicarboxylic-acid-diethyl-ester separated from the chloroform boils at a pressure of 0.1 mm. at 100 to 102° C.

186 parts by weight of sodium-iodide hydrate are added to a solution of 280 parts by weight of 2-methyl-3-chloro-thiophan-3,4-dicarboxylic-acid-diethyl-ester in 4000 parts by volume of 80 per cent. acetic acid, and 1400 parts by weight of zinc dust introduced in small portions in the course of about 4 hours while stirring. Each time slight warming sets in. After further stirring for about 12 hours, the zinc acetate is separated, the acetic acid removed by distillation and the residue distilled in vacuo after thoroughly washing with water and sodium carbonate solution. The 2-methyl-thiophan-3,4-dicarboxylic-acid-diethyl-ester boils at a pressure of 0.02 mm. at 88 to 90° C. as a colourless oil.

246 parts by weight of 2-methyl-thiophan-3,4-dicarboxylic-acid-diethyl-ester are dissolved in

250 parts by volume of absolute alcohol and the solution heated under reflux with 50 parts by weight of hydrazin hydrate for about 10 hours. After some time, the hydrazide begins to precipitate. The precipitate augments in the course of heating. After cooling, the 2-methyl-thiophan-3,4-dicarboxylic-acid-dihydrazide is separated, dissolved and allowed to crystallise from hot water. It melts at 241 to 242° C. after previous sintering.

A solution of 218 parts by weight of 2-methyl-thiophan-3,4-dicarboxylic-acid-dihydrazide in 670 parts by volume of 3 n-hydrochloric acid is covered with a layer of 2000 parts by volume of ether and a solution of 140 parts by weight of sodium nitrite in 800 parts by volume of water added drop by drop. The resulting acid azide is soluble in ether. The ether solution is separated from the salt solution when the reaction has come to an end, the ether driven off and the 2-methyl-thiophan-3,4-dicarboxylic-acid-diazide remaining behind as a light-yellowish oil is treated with 2000 parts by volume of absolute alcohol. The clear solution is heated to about 65° C., at which temperature a vigorous evolution of nitrogen sets in, which lasts for about half-an-hour. The clear, almost colourless solution is treated with water until it starts to get turbid and cooled. On filtering the colourless 2-methyl-3,4-di-(carbethoxyamino)-thiophan crystallising in fine needles of melting point 182 to 183° C. is obtained.

The same diurethan can be obtained by saponifying the 2-methyl-thiophan-3,4-dicarboxylic-acid-diethyl-ester, converting the resulting acid into the acid chloride (boiling point 12 mm./135-137° C.) and reacting the same with sodium azide. The resulting oily, ether-soluble diazide turns into the 2-methyl-3,4-(dicarbethoxyamino)-thiophan of melting point 182 to 183° C. on warming in absolute alcohol.

276 parts by weight of this urethane are heated for about 1 hour to 105 to 110° C. together with 2760 parts by volume of 45 per cent. hydrobromic acid until the evolution of carbonic acid has come to an end. On concentration in vacuo, the 2-methyl-3,4-diamino-thiophan-dihydrobromide remains behind as a solid mass. It can be dissolved and allowed to crystallise from a solution in dilute acetone or dilute alcohol. The colourless crystals, inclusive of 2 crystal-water, melt at 225 to 227° C. with decomposition. The diamine is characterised by the following derivatives:

The 2-methyl-3,4-diureido-thiophan melts at 262° C. with decomposition. The 2-methyl-3,4-diamino-thiophan-dipicrate melts at 243° C. with decomposition. The 2-methyl-3,4-di-(benzoyl-amino)-thiophan melts at 271-272° C. The 2-methyl-3,4-di-(acetylamino)-thiophan melts at 260-261° C.

330 parts by weight of 2-methyl-3,4-diamino-thiophan-dihydro-bromide are dissolved in 2000 parts by volume of n-sodium-hydroxide and well stirred while cooling. In order that a weakly alkaline reaction may always be prevailing, 2000 parts by volume of n-sodium-hydroxide, on the one hand, and 100 parts by weight of phosgene in form of a 20 per cent. solution in toluene, on the other hand, are simultaneously added drop by drop to the solution. Colourless crystals immediately begin to precipitate. Soon after the dropwise addition has come to an end, the reaction is complete. The crystal mash is filtered by suction and washed with water. The 3,4-(2'-oxo-tetrahydroimidazol)-2-methyl-thiophan can be

crystallised from a solution in dilute acetic acid or dilute alcohol. It is easily soluble in alcohols and acetic acid, less easily in acetone and difficultly in ether, benzene and water. It carbonises on prolonged heating to 350-360° C.

Example 2

80 parts by weight of finely pulverised potassium cyanide are added to a solution of 260 parts by weight of 2-(omega-methoxybutyl)-3-oxo-thiophan-4-carboxylic-acid-ethyl-ester in 540 parts by volume of dibutyl ether and then 106 parts by volume of concentrated hydrochloric acid allowed to drop in during 8 hours while stirring and cooling with ice. The reaction mixture is left to stand overnight at 0° C. The crystallised cyanohydrin with the potassium chloride is separated from the dibutyl-ether solution by suction. The separation of the cyanohydrin from the potassium chloride is effected by dissolving the former in chloroform. The chloroform solution is dried with sodium sulphate and after filtration brought to dryness in vacuo at a bath temperature of 30° C. The 2-(omega-methoxybutyl)-3-hydroxy-3-cyano-thiophan-4-carboxylic-acid-ethyl-ester, obtained in almost theoretical yield, has a melting point of 88° C. The methyl ester melts at 81.5 to 83.5° C.

287 parts by weight of 2(omega-methoxybutyl)-3-hydroxy-3-cyano-thiophan-4-carboxylic-acid-ethyl-ester are reacted with a mixture of 600 parts by volume of concentrated hydrochloric acid, 300 parts by volume of water and 1100 parts by volume of ethyl alcohol and boiled under reflux for 48 hours. After evaporation in vacuo, the saponified product is converted into the 2-(omega-methoxybutyl)-3-hydroxy-thiophan-3,4-dicarboxylic-acid-diethyl-ester by means of ethyl alcohol and hydrogen-chloride gas. It boils at a pressure of 0.07 mm. at 145-147° C. as a light-yellow, viscous oil. The dimethyl ester boils at a pressure of 0.09 mm. at 146-149° C.

334 parts by weight of 2-(omega-methoxybutyl)-3-hydroxy-thiophan-3,4-dicarboxylic-acid-diethyl-ester are dissolved in 660 parts by volume of chloroform and reacted with 154 parts by weight of absolute pyridine and 231 parts by weight of thionyl chloride while cooling with ice. Reaction and working-up in accordance with Example 1 yield a yellowish-brown, viscous oil, viz. 2-(omega-methoxybutyl)-3-chloro-thiophan-3,4-dicarboxylic-acid-diethyl-ester, melting point 138-143° C. at 0.03 mm. The dimethyl ester boils at 134 to 137° C. under a pressure of 0.03 mm.

353 parts by weight of 2-(omega-methoxybutyl)-3-chloro-thiophan-3,4-dicarboxylic-acid-diethyl-ester are dissolved in 5100 parts by volume of 80 per cent. acetic acid, 230 parts by weight of potassium iodide are added, and, while stirring, 1550 parts by weight of zinc dust are introduced in small portions in the course of 4 hours at a temperature not exceeding 20-25° C. After working-up in accordance with Example 1, the 2-(omega-methoxybutyl)-thiophan-3,4-dicarboxylic-acid-diethyl-ester boils as a light-yellowish oil at 148 to 150° C. under a pressure of 0.03 mm. The 2-(omega-methoxybutyl)-thiophan-3,4-dicarboxylic-acid-dimethyl-ester boils at 141 to 143° C. under a pressure of 0.03 mm.

318.5 parts by weight of 2-(omega-methoxybutyl)-thiophan-3,4-dicarboxylic-acid-diethyl-ester are dissolved in 1650 parts by volume of methanol and boiled under reflux for 72 hours with 200 parts by volume of hydrazin hydrate. On cooling, the 2-(omega-methoxybutyl)-thiophan-3,4-di-

carboxylic-acid-dihydrazide precipitates in colourless needles and has a melting point of 204 to 205° C. The same hydrazide is also obtained from the 2-(omega-methoxybutyl)-thiophan-3,4-dicarboxylic-acid-dimethyl-ester.

290 parts by weight of 2-(omega-methoxybutyl)-thiophan-3,4-dicarboxylic-acid-dihydrazide are dissolved in 835 parts by volume of 3 n-hydrochloric acid, covered with a layer of 8000 parts by volume of ether and reacted, while stirring and cooling with ice, with a solution of 138 parts by weight of sodium nitrite in 1000 parts by volume of water added drop by drop. The azide is isolated as described in Example 1 and transformed into the urethane by means of 7000 parts by volume of absolute alcohol. The fine, colourless needles of 2-(omega-methoxybutyl)-3,4-diurethano-thiophan show a melting point of 157° C.

348 parts by weight of 2-(omega-methoxybutyl)-3,4-diurethano-thiophan are heated to 100 to 105° C. with 4000 parts by volume of 48 per cent. hydrobromic acid until the evolution of carbonic acid ceases. After evaporation of the hydrobromic acid in vacuo, the dihydrobromide remains behind as a solid mass. After dissolving in and allowing to crystallise from a little water and acetone, the 2-(omega-bromobutyl)-3,4-diamino-thiophan-dihydrobromide has a melting point of 217° C.

415 parts by weight of 2-(omega-bromobutyl)-3,4-diamino-thiophan-dihydrobromide are dissolved in 2000 parts by volume of n-sodium-hydroxide, and while cooling with ice and while stirring, reacted with 99 parts by weight of phosgene (in the form of a 20 per cent. solution in toluene) and 2000 parts by volume of n-sodium hydroxide, the latter and the toluene-phosgene solution being added simultaneously and the reaction being effected at a pH of 7 to 8. The reaction product, after addition of glacial acetic acid, is brought to dryness in vacuo and rubbed with water. The 3,4-(imidazolidon-2')-2-(omega-bromobutyl)-thiophan has a melting point of 175.5° C. after dissolving and allowing to crystallise from methanol.

Example 3

Apart from the crystallised dihydrazide of melting point 204 to 205° C. obtained as a result of the preparation of 2-(omega-methoxybutyl)-thiophan-3,4-dicarboxylic-acid-dihydrazide in accordance with Example 2, also an oily compound is isolated from the mother liquors.

290 parts by weight of this oily dihydrazide are converted into the urethane in the same manner as in the case of the crystallised dihydrazide (cf. Example 2). The product obtained, which contains a mixture of stereoisomers, is dissolved in benzene and chromatographed on a column of aluminum oxide. One of the isomeric urethanes, having a melting point of 125 to 126° C., is obtained in crystalline form by eluting with benzene.

348 parts by weight of 2-(omega-methoxybutyl)-3,4-diurethano-thiophan of melting point 125 to 126° C. are heated with 48 per cent. hydrobromic acid as described in Example 2. The resulting hygroscopic 2-(omega-bromobutyl)-3,4-diamino-thiophan-dihydro-bromide is converted into the 3,4-(imidazolidon-2')-2-(omega-bromobutyl)-thiophan by means of phosgene. The crystallised compound, after recrystallisation from methanol, has a melting point of 163 to 164° C.; the mixture with the isomer of melting point

175.5° C. shows considerable depression of the melting point.

On chromatographically treating the oily urethanes, further isomers are obtained which can be worked up in the same manner.

We claim:

1. Process for the manufacture of a d,l-substance of the general formula

wherein the radical **X** is selected from the group consisting of alkyl, omega-methoxy alkyl and omega-halogeno alkyl, comprising converting 3-oxo-thiophan-4-carboxylic-acid-esters, which are substituted in position 2 by the radical **X**, into the cyano-hydrides, preparing therefrom by saponification and esterification the corresponding 3-hydroxy-3,4-dicarboxylic-acid-esters, eliminating from these compounds the hydroxy-group by replacing it by halogen and subsequently reducing the latter, reacting the thus obtained thiophan-3,4-dicarboxylic-acid-esters, carrying the radical **X** in position 2, with hydrazin hydrate, reacting upon the acid hydrazides with sodium nitrite in order to obtain the acid azides and decomposing the latter by reacting with alcohol to yield the 3,4-diurethans, converting these by boiling with acids into the salts of the 3,4-diamino-thiophans substituted in position 2 by the radical **X**, and obtaining from these diamines the 2-**X**-3,4-(2'-oxo-tetrahydroimidazol)-thiophans by means of phosgene.

2. Process for the manufacture of d,l-2-methyl-3,4-(2'-oxo-tetrahydroimidazol)-thiophan, comprising converting 2-methyl-3-oxo-thiophan-4-carboxylic-acid-esters into the cyano-hydrides, preparing therefrom by saponification and esterification the corresponding 3-hydroxy-3,4-dicarboxylic-acid-esters, eliminating from these compounds the hydroxy-group by replacing it by halogen and subsequently reducing the latter, reacting the thus obtained 2-methyl-thiophan-3,4-dicarboxylic-acid-esters with hydrazin hydrate, reacting upon the acid hydrazides with sodium nitrite in order to obtain the acid azides and decomposing the latter by reacting with alcohol to yield the 3,4-diurethans, converting these by boiling with acids into the salts of the 2-methyl-3,4-diamino-thiophans and obtaining from these diamines the 2-methyl-3,4-(2'-oxo-tetrahydroimidazol)-thiophans by means of phosgene.

3. Process for the manufacture of d,l-2-(omega-methoxy-butyl)-3,4-(2'-oxo-tetrahydroimidazol)-thiophan, comprising converting 2-(omega-methoxy-butyl)-3-oxo-thiophan-4-carboxylic-acid-esters into the cyano-hydrides, preparing therefrom by saponification and esterification the corresponding 3-hydroxy-3,4-dicarboxylic-acid-esters, eliminating from these compounds the hydroxy-group by replacing it by halogen and subsequently reducing the latter, reacting the thus obtained 2-(omega-methoxy-butyl)-thiophan-3,4-dicarboxylic-acid-esters with hydrazin hydrate, reacting upon the acid hydrazides with sodium nitrite in order to obtain the acid azides and decomposing the latter by reacting with alcohol to yield the 3,4-diurethans, converting these by boiling with acids into the salts of the 2-(omega-methoxy-butyl)-3,4-(2'-oxo-tetrahydroimidazol)-thiophans by means of phosgene.

4. Process for the manufacture of d,l-2-(omega-bromo-butyl)-3,4-(2'-oxo-tetrahydroimidazol)-

thiophan, comprising converting 2-(omega-bromo-butyl)-3-oxo-thiophan-4-carboxylic-acid-esters into the cyano-hydrides, preparing therefrom by saponification and esterification the corresponding 3-hydroxy-3,4-dicarboxylic-acid-esters,

5. eliminating from these compounds the hydroxy-group by replacing it by halogen and subsequently reducing the latter, reacting the thus obtained 2-(omega-bromo-butyl)-thiophan-3,4-dicarboxylic-acid-esters with hydrazin hydrate, reacting upon the acid hydrazides with sodium nitrite in order to obtain the acid azides and decomposing the latter by reacting with alcohol to yield the 3,4-diurethans, converting these by boiling with acids into the salts of the 2-(omega-bromo-butyl)-3,4-diamino-thiophans and obtaining from these diamines the 2-(omega-bromo-butyl)-3,4-(2'-oxo-tetrahydroimidazol)-thiophans by means of phosgene.

10. 5. As compositions of matter, d,l-2-substituted-3,4-(2'-oxo-tetrahydroimidazol)-thiophans, in which the substituent in the 2-position is a member selected from the group consisting of alkyl radicals and aliphatic omega-substituted-alkyl radicals.

15. 6. As compositions of matter, d,l-2-substituted-3,4-(2'-oxo-tetrahydroimidazol)-thiophans, in which the substituent in the 2-position is alkyl.

20. 7. As compositions of matter, d,l-2-substituted-3,4-(2'-oxo-tetrahydroimidazol)-thiophans, in which the substituent in the 2-position is aliphatic omega-substituted-alkyl.

25. 8. As compositions of matter, d,l-2-substituted-3,4-(2'-oxo-tetrahydroimidazol)-thiophans, in which the substituent in the 2-position is methyl.

30. 9. As compositions of matter, d,l-2-substituted-3,4-(2'-oxo-tetrahydroimidazol)-thiophans, in which the substituent in the 2-position is omega-alkoxy-alkyl.

35. 10. As compositions of matter, d,l-2-substituted-3,4-(2'-oxo-tetrahydroimidazol)-thiophans, in which the substituent in the 2-position is omega-alkoxy-butyl.

40. 11. As compositions of matter, d,l-2-substituted-3,4-(2'-oxo-tetrahydroimidazol)-thiophans, in which the substituent in the 2-position is omega-methoxy-butyl.

45. 12. As compositions of matter, d,l-2-substituted-3,4-(2'-oxo-tetrahydroimidazol)-thiophans, in which the substituent in the 2-position is omega-halogeno-alkyl.

50. 13. As compositions of matter, d,l-2-substituted-3,4-(2'-oxo-tetrahydroimidazol)-thiophans, in which the substituent in the 2-position is omega-bromo-alkyl.

55. 14. As compositions of matter, d,l-2-substituted-3,4-(2'-oxo-tetrahydroimidazol)-thiophans, in which the substituent in the 2-position is omega-bromo-butyl.

60. 15. A process of synthesizing d,l-2-substituted-3,4-(2'-oxo-tetrahydroimidazol)-thiophans, which comprises converting 2-substituted-3,4-di-carbalkoxyamino-thiophans, in which the substituent in the 2-position is a member selected from the group consisting of alkyl radicals and aliphatic omega-substituted-alkyl radicals, to d,l-2-substituted-3,4-(2'-oxo-tetrahydroimidazol)-thiophans, in which the substituent in the 2-position is a member selected from the group consisting of alkyl radicals and aliphatic omega-substituted-alkyl radicals.

65. 16. A process in accordance with claim 15 which comprises converting the di-carbalkoxyamino-thiophan to a di-hydrohalide salt of 2-substituted-3,4-diamino-thiophan by means of a hydro-

70. 75.

halide acid, and converting the said salt to the imidazol thiophan.

17. A process in accordance with claim 15 which comprises converting the di-carbalkoxyamino-thiophan to a di-hydrobromide salt of 2-substituted-3,4-diamino-thiophan by means of hydrobromic acid, and converting the said salt to the imidazol thiophan.

18. A process in accordance with claim 15 in which the carbalkoxyamino is carbethoxyamino.

19. A process in accordance with claim 15 in which a 2-substituted-3,4-di-(carbethoxyamino)-thiophan, in which the substituent is a member selected from the group consisting of alkyl and aliphatic omega-substituted-alkyl radicals, is con- 15

verted to a di-hydrobromide-amino salt by means of hydrobromic acid, followed by conversion of said salt to the imidazol-thiophan.
